HAIR DRIER

Filed Dec. 16, 1929

UNITED STATES PATENT OFFICE

LESLIE W. COOLEY AND DAMON R. WARD, OF DENVER, COLORADO

HAIR DRIER

Application filed December 16, 1929. Serial No. 414,517.

Our invention relates to hair dryers. An object of the invention is to provide an apparatus that will dry and heat air before it is drawn through a person's hair.

5 Another object is to provide means to circulate air past a heating element, through a person's hair and back past the heating element again, and so on.

10 A further object is to provide means for the removal of moisture from the air during its circulation.

Still other objects reside in novel details of construction and in novel combinations and arrangements of parts, which will more fully 15 appear in the course of the following description.

In the drawing like reference characters designate similar parts in the several views.

20 Figure 1 is an elevation, partly in section, of an apparatus embodying the present invention.

Figure 2 is an end elevation, looking in the direction of the arrow "A" of Figure 1.

25 Figure 3 is a section taken on the line 3—3 of Figure 1.

Figure 4 is a diagram of the wiring of the present apparatus.

Referring more specifically to the drawing, 30 the reference numeral 5 designates a base for the apparatus, having feet 6. Telescoping with the base 5 is a standard 7 that is adjustable with relation to the base by means of a set screw 8. A motor housing is shown at 9. The housing encloses the motor indicated at 35 9 in Figure 4.

A band 10 around the motor housing is bolted to one arm of a bell crank 12. The bell crank is pivoted on a yoke 13 on the standard. The other arm of the bell crank carries a segmental arm 14. The segment 40 passes through an opening 15 in the yoke and is held in its desired positions by a set screw 16.

The motor housing has a rim 17 upon which 45 one end of a hood 18 is slipped and thereby supported. The opposite end of the hood has an inwardly extending flange 63 and provides an open end 19 for the reception of a person's head. The open end 19 has a curved recess 20 for the user's neck. A strip of rubber

padding 21 covers the edge of the flange 63 and the edge of the neck recess. A fabric pad 22 extends across the neck recess 20 and makes a closer fit around the user's neck.

55 A fan 23 is connected with the motor and disposed within the hood 18. The fan is preferably of the type that creates suction and also is a blower, such, for instance, as is used in vacuum cleaners.

60 Spaced interiorly from the walls of the hood is a shell 24, which is fastened to the motor housing by lugs 25. The shell has an opening 26 adjacent to the opening 19 of the hood, in which the user's head is placed. The opening 26 also has a recess 27 for the user's neck. Between the shell and hood is a space 60 approximately the width of the flange 63, so that the flange may direct inwardly air forced through the space 60 toward the open end 19. The outer open end of the shell 24 terminates short of the outer open end of the hood 18 and the inwardly extending flange 63, and forms a space between the flange and shell to accommodate a portion of the user's hair and into which the air circulated by the fan 23 through the space 60 is admitted. The air entering the space is directed by the flange 63 through the hair of the user in the space and thence into the shell 24 and then through 65 the heating chamber 56 for recirculation.

70 75 80 In the space 60 are two heating coils 31 and 32 supported around the shell by a series of porcelain bridges 29 mounted on a band 30 on the shell. The coils heat the adjacent interior of the shell, as well as the space 60. A modified construction, however, is to make 85 the band 30 of asbestos. Ribs 49 arranged longitudinally with respect to the shell 24 provide air channels thereon to prevent the air from whirling in the space 60.

85 The coils are in different circuits. The motor is in both circuits, as shown in Figure 4. A source of electrical energy is indicated at 28. A manually operated switch 33 controls the circuits of both of the heating coils 90 and of the motor.

95 The circuits of the coil may be traced from the source 28, through the switch 33, rheostat 42, wire 36, the coil 31, and wires 37 and 38 back to the source. The motor 9 is wired 100

in parallel with the coil 31. The motor circuit may be traced from the source through the wire 39, the motor, wires 35 and 45, and through the switch 33 back to the source.

5 The rheostat is controlled by a wire 46 in a flexible sheath 47. The wire 46 has a loop 48 at an end within easy reach of the user.

The circuit of the coil 32 is closed by the manual switch 41. This circuit may be 10 traced from the source, through the switch 33, wire 43, the coil 32, wire 44, the switch 41 and wires 45 and 38 back to the source.

Partitions 50 and 51 define a heating chamber 56 within the shell, which is heated by 15 the surrounding coils. The partition 50 is shaped similarly to the contour of the back of a person's head and has a square opening 52 and a series of holes 53 around the opening. Bars 54 prevent the hair of the user 20 from being drawn through the opening 52 into the fan. Ribs 57 are disposed opposite each other on the lower half of the shell 24. These ribs turn the air towards the back of the user's head, immediately behind his ears.

25 The partition 51 has a central, circular opening 55 connecting the heating compartment 56 with the fan chamber. Between the lugs 25 are openings 58 that connect the interior of the shell with the space between 30 the shell and hood. The shell has vanes 59 adjacent the open end to hold the user's head in spaced relation to the shell and also to provide air channels for directing the currents of air through the shell.

35 A slot 61 in the hood near the openings 58 and adjacent the fan provides a discharge outlet for moisture and moisture-laden air. The moisture-carrying air is heavier than the heated air and so finds its way through 40 the slot 61 by reason of the centrifugal force produced by the fan.

In the operation of the apparatus, a user places his head in the open ends of the hood and shell, as shown in dotted lines in Figure 45 1. The operator closes the switches 33 and 41, which causes both coils to heat. The coil 32 is only used for the initial heating. As soon as the temperature has risen high enough, the operator opens the switch 41.

50 The heat of the coil 31 is thereafter controlled by the user through the medium of the rheostat operated by the wire 46.

The fan draws air into the shell past the user's head, through the openings in the 55 partition 50, through the heating compartment 56, then blows it through the openings 58 into the space 60 between the shell and hood, and past the heating coils to the user's head. As the air reaches the end openings of 60 the shell and hood, it is again drawn into the shell. It will thus be seen that the heated air circulates through the apparatus and through the user's hair.

The motor is stopped by moving the switch 65 33 to an open position.

It is apparent that changes may be made in the construction and arrangement of parts without departing from the scope of the invention.

What we claim is:

1. A hair drier comprising a flanged hood, a shell in the hood, spaced therefrom to provide a circulating space, the flange of the hood extending across said space to direct air therefrom toward the shell, a fan disposed in one end of the hood to force air through the space and to draw the air back through the shell after being directed toward the shell by the flange, and a heater in the path of the air.

2. A hair drier comprising a shell, a flanged hood around the shell, spaced therefrom, and projecting beyond the open end of the shell, the flange extending across said space to direct air in the projecting portion of the hood, toward the shell, a fan disposed in one end of the hood and extending into the shell to move air through said space, through said projecting portion of the hood, and through the shell, and a heater in the path of the air.

3. A hair drier comprising a hood and a shell spaced therefrom to provide a circulation space, the shell having openings connecting the space between the hood and the shell with the interior of the latter and the hood and the shell having open ends to admit the head of a user, a fan in the shell and a heater in the path of air circulating through the hood and the shell by action of the fan.

4. A hair drier comprising a hood and a shell spaced therefrom to provide a circulation space, the shell having openings connecting the space between the hood and the shell with the interior of the latter and the hood and the shell having open ends to admit the head of a user, a fan in the shell and a heater in said space, and vanes extending inwardly of the shell to space user's head therefrom and provide channels for circulation of the air therethrough.

5. A hair drier comprising a hood and a shell spaced therefrom to provide a circulation space, the shell having openings connecting the space between the hood and the shell with the interior of the latter, the hood having openings for the discharge of moisture-laden air, and the hood and the shell having open ends to admit the head of a user, a fan in the shell and a heater in the path of air circulating through the hood and the shell by action of the fan.

6. A hair drier comprising a hood having an open end to admit the head of a user, a fan in the hood, a heater in the hood, means in the hood cooperating with the fan to compel air drawn into the hood to move in a closed circulatory path including the heater and the portion of the head of the user, and

means in the hood to divert air moving in said path, upwardly toward the head of the user.

7. A hair drier comprising a hood having an open end to admit the head of a user, an electric heater in the hood, means to effect a circulatory movement of air within the hood, in a path including the head of the user, within the same, and the heater, oppositely disposed ribs in the lower portion of the shell adjacent its open end to direct air towards the back of user's head immediately behind the ears, a circuit for the heater, a variable resistance in the circuit, and means accessible to the user, to control the resistance.

8. A hair drier comprising a hood having an open end to admit the head of a user, a heater in the hood, a shell in the hood, means to effect a circulatory movement of air within the hood and shell, in a path including the head of the user, within the same, and the heater, vanes within the shell to space user's head therefrom and forming channels for directing air through the shell, a regulator for the heater, and means accessible to the user, to control the regulator.

9. A hair drier comprising a hood having an open end to admit the head of a user, an electric heater in the hood, a shell in the hood, means to effect a circulatory movement of air within the hood and shell, in a path including the head of the user, within the same, and the heater, oppositely disposed ribs in the lower portion of the shell to direct air towards the back of user's head, the heater having two heating units, a circuit for the units, a switch adapted to exclude one unit from the circuit separate from the other unit, and a variable resistance in the circuit.

10. A hair drier comprising a hood having an open end to admit the head of a user, a shell in the hood, an electric heater in the hood, a fan in the hood to effect a circulatory movement of air within the hood and shell,

45 in a path including the head of the user, within the same, and the heater, vanes extending inwardly from the shell to space user's head therefrom and provide air channels for directing air through the shell, the 50 heater having two heating units, an electric motor for the fan, an electric circuit for the heating units and the motor, and a switch adapted to exclude one of the heating units from the circuit, separate from the other unit 55 and the motor.

11. A hair drier comprising a hood, a shell within the hood and spaced therefrom to provide an annular air circulating space, said hood and shell having one of their ends open, 60 a fan in the other end of the hood for forcing air through said space, a member in the shell spaced forwardly of the fan and forming a heating chamber between the fan and said member, a heater associated with said chamber, whereby air forced through said space is

drawn by suction of the fan through the heating chamber and recirculated through said annular circulating space.

12. A hair drier comprising a hood, a shell within the hood and spaced therefrom to provide an annular air circulating space, said hood and shell having one of their ends open, a fan in the other end of the hood for forcing air through said space, a member provided with openings in the shell spaced forwardly of the fan and forming a heating chamber between the fan and said member, a heater associated with the said chamber and extending into said space, whereby air forced through said space is heated by the heater and is drawn through the openings in the said member into the interior of the heating chamber by suction of the fan and recirculated through said space.

13. A hair drier comprising a hood having an open end provided with an inwardly extending flange and adapted to admit the head of the user, a shell having an open end spaced from the outer shell within the hood forming an annular air space, said shell terminating short of the open end of the hood and spaced from the flange, thereby forming a space between the flange and shell, means in the other end of the hood to circulate air in the space between the hood and shell whereby the air may impinge said flange and be directed toward the interior of said shell to be recirculated.

14. A hair drier comprising a shell having an open end to admit the head of a user, a fan in the shell, a heater on the outside of the shell, and means cooperating with the fan to compel air drawn into the shell to move in a closed circulatory path including the heater and the portion of the head of the user inside the shell.

In testimony whereof we have affixed our signatures.

DISCLAIMER

1,899,261.—*Leslie W. Cooley and Damon R. Ward, Denver, Colo. HAIR DRIER.*
Patent dated February 28, 1933. Disclaimer filed February 5, 1935, by
the assignee, *The Martin Brothers Electric Company*.

Hereby disclaims claim 13 which reads as follows:

“13. A hair drier comprising a hood having an open end provided with an inwardly extending flange and adapted to admit the head of the user, a shell having an open end spaced from the outer shell within the hood forming an annular air space, said shell terminating short of the open end of the hood and spaced from the flange, thereby forming a space between the flange and shell, means in the other end of the hood to circulate air in the space between the hood and shell whereby the air may impinge said flange and be directed toward the interior of said shell to be recirculated.”
